UNITED STATES PATENT OFFICE

ALBERT S. RAIRDEN, OF HAMDEN, CONNECTICUT

MANUFACTURE OF DEAD LAY WIRE ROPE

Application filed July 11, 1927. Serial No. 204,916.

This invention relates to the manufacture of "dead lay" wire rope and more particularly to a novel method of and apparatus for manufacturing such rope, and has for its object the provision of a novel method which may be carried out on standard vertical rope laying machines by making slight changes in the twisting heads thereof.

The apparatus for carrying out my novel method will be illustrated as embodied in a double deck vertical laying-up machine. However, it will be understood that I do not wish to be limited thereto since it may be also readily applied to horizontal or other types of rope laying machines.

In the drawings—

Figure 1 is a vertical sectional elevation through a laying-up machine constructed in accordance with, and for carrying out the method of, this invention.

Figure 2 is a detail plan of the head portion of the machine.

Figure 3 is an elevation of the head portion of the machine.

Figure 4 is a sectional elevation through the head of the machine.

Figure 5 is a fragmentary plan illustrating the arrangement of drive gearing for the machine.

Figure 6 is a detailed sectional elevation through the lower end of the machine showing the gearing.

Referring more particularly to the drawings, the numeral 2 designates the base of the machine which includes a bearing support 3 for the lower end of a vertical shaft or mast 4 which has an opening or bore 4^a throughout its length, through which the core member 4^b of the rope is adapted to be passed to the twister head.

The upper end of the shaft 4 is provided with a sleeve-head 5 to which a spider ring 6 is secured which serves as a strand guide and bending ring and also as a bearing for the upper end of the shaft.

The ring 6 is journaled in a supporting bracket 7 which in turn is secured to any suitable supporting structure indicated at 8, such as the girders of the building in which the machine is housed.

A twister-head comprising a stem or plug portion 9, adapted to be inserted in the upper end of sleeve-head 5 and a disk portion 10, is provided for twisting or laying the strand wires up around the core. The twister-head and sleeve-head 5 are both apertured in line with the bore 4^a of the shaft 4 to permit the core member of the rope to be passed centrally therethrough.

The disk portion 10 of the twister-head is of a materially greater diameter than the ring 6, for a purpose to be described, and is also provided with slots or grooves 12 in its peripheral edge to receive the strand wires of the cable or rope. The bottom walls of the slots or grooves 12 are inclined inwardly from bottom to top and said slots or grooves are of such depth that their bottom walls will be spaced materially outward beyond the inner periphery of the ring 6.

Three spider rings 14 are secured at spaced intervals of the shaft 4 and form supports for a plurality of cradles or strand spool supports 15. The spaces between the rings 14 are what are known as bays or decks, and since there are two of such spaces in the present embodiment of the invention, the machine shown is known as a two-bay or two-deck machine.

Spools 16 of strand wires or twisted strands 16^a are journaled in the supports 15 and the strands are trained from the spools 16 upwardly through the ring 6, then outwardly and into the respective slots 12 in the twister-head, and then are reversed inwardly to a central point where they are laid around the core strand.

The point of lay is defined by a die 18 carried by a cross-head 19 adjustably mounted on a pair of threaded bars 20, which bars are mounted in the support 7. Nuts 21 are provided on the bars 20 for locking the cross-head in its vertical adjusted position.

The spool supports 15 are each journaled at their upper ends in the spider rings 14, and have their lower ends keyed to shafts 25. All of the shafts 25 extend downwardly to a common level and are provided with pinions 26 which are in mesh with idler pinions 27 on stub shafts 28 carried by the lower spider

ring 14. All of the idler pinions 27 are also in mesh with a common drive-gear 29 journaled on the shaft 4 and provided with an extended collar portion 29^a. A worm-wheel 5 29^b is keyed to the collar 29^a and meshed with a worm 29^c on a power shaft 30^a, whereby the gear 29 is operated so as to drive the pinions 27 and 26. The driving of the pinions 27 and 26 will cause a planetary motion to be transmitted 10 to the spools to retain the spools in the same relative plane with the central shaft 4 of the machine at all times.

The shaft 4 is provided with a ring-gear 30 which is in mesh with a bevel pinion 31 on a power shaft 32 whereby, when power is applied 15 to the shaft 32, the shaft or mast 4 will be rotated.

The finished rope passes from the die 18 over a sheave 35 and then to a suitable stand-20 ard take-up and pull-out mechanism 36.

In carrying out my novel method, the core strand 4^b is trained up through the bore 4^a of the shaft or mast 5, and through the die 18.

The strands 16^a will be trained upwardly 25 from each of the spools 16, through the spiders 14 and through the ring 6, then outwardly and upwardly to the slots or grooves 12 in the deck portion 10 of the twister-head, then said strands are trained on a reverse angle 30 inwardly and upwardly, and through the die 18. From the die 18 the core 4^a and strands 16^a are either trained over the sheave 35 and down to the take-up and pull-out mechanism 36 or are secured to a lead cable which in 35 turn is secured to the take-up and pull-out mechanism 36. The laying-up machine and take-up and pull-out mechanism are then operated. The take-up and pull-out mechanism 36 will pull the core 4^a and strands 16^a 40 through the laying-up machine and the twister-head disk 10 will lay the strands spirally around the core member 4^a.

As the strands 16^a are pulled over the edge of the disk 10 of the twister-head they are 45 under tension due to the reverse bend at this point caused by passing the strands through the ring 6, then over the disk 10 and then inwardly to the die. By passing or pulling the strands over the edge of the disk 10 under 50 tension and at the same time transmitting a planetary motion to the spools 16 carrying the strands, so as to retain the spools in the same relative plane with the axis of the central shaft 4 and twister-head disk 10, the one 55 and same side of the strands throughout the entire length of the strands will be worked or stretched by frictional contact with the disk 10, while the opposite side of the strand will remain unstretched, thus setting up internal 60 stresses which will cause the strands to coil or assume a helical shape prior to laying up the strands.

The amount of stretch given to the strands is gaged so that the degree of the helixes 65 formed by the stresses is the same or substan-

tially the same as the degree of the helixes of the lay of the strands, and since the stretch of the strands varies in proportion to the tension of the strands as they are pulled over the disk 10, the degree of the helixes can be readily 70 adjusted to suit the lay of the strands by adjusting the vertical position of the die 18 which will vary the tension on the strands.

It will be understood that the above method may be carried out on other forms of laying-up and stranding machines than that illustrated and described. The essential feature being the provision of suitable mechanism whereby one side of the strands in a rope, or wires in a strand may be stretched relative 75 to the other side so that internal stresses will be set up in said strands or wires to cause 80 said strands or wires to assume a helical shape prior to laying up of the strands or stranding 85 of the wires.

I claim—

1. In a dead lay rope machine for laying up dead lay wire rope, a central hollow shaft through which the core is adapted to be 90 passed, a plurality of strand spools carried by and rotatable with said shaft, a twister-head secured to one end of said shaft, a combined guide and bending ring secured to said shaft at a point slightly below said head, said ring being of materially less diameter than said 95 head, and a die adjustably mounted above said head.

2. In a dead lay rope machine for laying up dead lay wire rope, a central hollow shaft through which the core is adapted to be 100 passed, a plurality of strand spools carried by and rotatable with said shaft, means for transmitting a planetary motion to said spools to retain said spools in the same relative plane with said central shaft throughout the rotation of said central shaft, a twister-head secured to one end of said shaft, a combined 105 guide and bending ring secured to said shaft at a point slightly below said head, said ring being of materially less diameter than said head, and a die adjustably mounted above 110 said head.

In witness whereof, I have hereunto signed my name.

ALBERT S. RAIRDEN.
